(57) **CLAIM**

I claim the ornamental design for a mobile party credenza having a pop-up top, as shown and described.

DESCRIPTION

FIG. 1 is a perspective view of a mobile party credenza having a pop-up top in its raised position showing my design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a mobile party credenza having a pop-up top in its lowered position;

FIG. 9 is a perspective view of a second embodiment of a mobile party credenza having a pop-up top in its raised position showing my design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is a perspective view of a mobile party credenza having a pop-up top in its lowered position.

The broken lines are for environmental purposes only and form no part of the claimed design. The broken lines within the credenza represent boundaries, form no part of the claimed design, and the areas within them also form no part of the claimed design.
